UNITED STATES PATENT OFFICE.

KARL DAVID SMITH, OF BATTLE CREEK, MICHIGAN, ASSIGNOR TO UNION STEAM
PUMP COMPANY, OF BATTLE CREEK, MICHIGAN.

DESIGN FOR A PUMP-BASE.

45,822.

Specification for Design.

Patented May 19, 1914.

Application filed March 30, 1914. Serial No. 828,405. Term of patent 14 years.

To all whom it may concern:

Be it known that I, KARL DAVID SMITH, a citizen of the United States, residing at Battle Creek, in the county of Calhoun, State of Michigan, have invented a new, original, and ornamental Design for a Pump-Base, of which the following is a specification, reference being had to the accompanying drawing, forming a part thereof.

The figure is a perspective view of a pump base, showing my new design.

I claim:

The ornamental design for a pump base, as shown.

KARL DAVID SMITH.

Witnesses:

EARL E. HAYWARD,
E. REEVES.
